UNITED STATES PATENT OFFICE

RALPH J. MEYER, OF DENVER, COLORADO

APPARATUS FOR MINING

Application filed September 11, 1930. Serial No. 481,147.

My invention consists of an improved apparatus for breaking coal deposits without the use of explosives.

Another object is to provide a simple and efficient device for carrying the above stated method into practise.

In the accompanying drawing in which like reference characters designate corresponding parts in the two views,

10 Figure 1 is a longitudinal section of the device in its operative position in a bore of a coal formation, and

Figure 2 is a transverse section along the line 2—2, Figure 1.

15 The device consists of a flexible tubular bag 5 reenforced at its ends, as shown at 6 and 7. The reenforced front end of the tube has an axial bore for the insertion of a nozzle-pipe 8 which at its outer extremity connects 20 with the flexible delivery-conduit 9 of a source of fluid-pressure, indicated at 10, by means of a coupling 12.

25 A rod, cable or other similar brace 13, extending lengthwise through the tube, is anchored in the reenforced end-portions thereof, by means of metal plates 14 and 15, and serves to prevent excessive elongation of the bag by the pressure fluid admitted thereto through the nozzle-tube 8.

30 In the operation of the device, the tubular bag is inserted in a hole 16 bored in the usual manner in an earth formation, shown at 17, it being desirable that the tube fits within the bore. The nozzle-tube projecting outside the 25 bore, is connected with a source of fluid under pressure, water or other liquid being preferred.

35 The fluid entering the bag, inflates the flexible wall 18 thereof, and the pressure exerted by the fluid upon the coal formation through the intermediary of the wall, will break and disrupt the coal or other substance and thus facilitates its removal without the use of explosives. The rod or cable extending through 45 the bag prevents its stretching lengthwise, so that the entire force of the fluid is directed laterally upon the flexible wall of the tube.

40 It is to be understood that while my invention is particularly adapted for use in mining coal, it may be used with equally satisfac-

tory results in breaking other substances. The device as shown in the drawing is preferred by reason of its simplicity, but changes and modifications in the construction thereof may be made within the scope of the appended claims.

45 The use of explosives in mining is always connected with a certain amount of risk and danger and these hazards are entirely avoided by the use of the present invention.

50 Any fluid-pressure may be employed within the scope of the invention, although the use of hydraulic pressure is preferred.

55 The reenforced front-end of the bag tapers to the flexible wall of the same to produce a gradually diminishing resistance to the expansive pressure of fluid admitted to the bag through the bore. This is of particular value when the resistance to the disruptive action of the expanding bag is less at the mouth of the hole 16, as usually occurs, particularly when the formation in which the hole is formed, is undercut.

60 What I claim and desire to secure by Letters Patent is:

65 1. An appliance of the character described comprising a one-piece bag having a tubular flexible wall integral with comparatively heavy end-portions, one of said end-portions having a bore to admit a pressure-fluid to the bag, and means for supplying a pressure fluid to the bore.

70 2. An appliance of the character described comprising a one-piece bag having a tubular flexible wall integral with comparatively heavy end-portions, one of said end-portions tapering interiorly of the bag to the flexible wall, and having a bore to admit a pressure-fluid to the bag, and means for supplying a pressure fluid to the bore.

75 3. An appliance of the character described comprising a one-piece bag having a tubular flexible wall integral with comparatively heavy end-portions, one of said end-portions having a bore to admit a pressure-fluid to the bag and tapering interiorly of the bag from the bore to the flexible wall, and means for supplying a pressure fluid to the bore.

80 4. An appliance of the character described comprising a one-piece bag having a tubular

flexible wall integral with comparatively heavy end-portions, one of said end-portions having a bore to admit a pressure-fluid to the bag, a brace extending interiorly of the bag and anchored in its end-portions to oppose excessive elongation, and means for supplying a pressure fluid to the bore.

5 5. An appliance of the character described comprising a one-piece bag having a tubular flexible wall integral with comparatively heavy end-portions, one of said end-portions having a bore to admit a pressure-fluid to the bag, anchors embedded in the end portions, a brace extending interiorly of the bag, in connection with the anchors, and means for supplying a pressure fluid to the bore.

10 6. An appliance of the character described comprising a one-piece bag having a tubular flexible wall integral with comparatively heavy end-portions, one of said end-portions tapering interiorly of the bag to the flexible wall and having a bore to admit a pressure-fluid to the bag, a brace extending interiorly of the bag and anchored in the end portions to oppose excessive elongation, and means for supplying a pressure fluid to the bore.

15 In testimony whereof I hereunto affix my signature.

RALPH J. MEYER.
